VALVE FOR WELL TESTING TOOLS

Filed Aug. 28, 1951

UNITED STATES PATENT OFFICE

2,667,927

VALVE FOR WELL TESTING TOOLS

Mordica O. Johnston, Glendale, Calif.

Application August 28, 1951, Serial No. 244,078

2 Claims. (Cl. 166—1)

1

This invention relates to an oil well tool and particularly to an oil well tool adapted to be incorporated in a formation tester or similar device.

Although the present invention will be described in connection with a formation tester, the invention is not intended to be necessarily limited to such use.

In making formation tests, it is usual practice to lower a formation tester into the well and seal off or block off the well bore or casing with a packer carried by the formation tester so as to separate the lower testing zone from the upper well fluid. It is also usual practice to thereafter open the formation tester to the formation zone and take a test of the connate or formation fluid by entrapping a body of this fluid within the formation tester.

It is a main object of the present invention to provide a simple and inexpensive tool for carrying out the above operations.

It is a more particular object of the present invention to provide such a tool having a tubular housing slidably but non-rotatably receiving a tubular mandrel, said tubular mandrel having the lower end thereof laterally ported to provide valve ports, which ported portion is adapted to be projected from within the walls of a small bore into a large bore for the purpose of admitting formation fluid to within the tubular mandrel, and then to be retracted to within the walls of the small bore to close the valve ports and entrap a connate sample within the tubular mandrel and the drill string thereabove, which tool also includes a strong compression spring disposed between the tubular mandrel and housing normally operable to position the tubular mandrel and housing with respect to one another so as to dispose the valve ports in closed position, but which spring can be compressed by a partial imposition of the weight of the drill string on the tubular mandrel to thereby project the ported portion of the mandrel.

Normally, the interior of the formation tester is at approximately atmospheric pressure, whereas the pressure of the formation zone is normally very high, therefore, the formation fluid obviously jets into the formation tester at an extremely high velocity.

Another object of the present invention is to provide a tool as above described in which the lower end of the mandrel below the ports carries packing for sealingly engaging the walls of the small bore, and which tool further includes means disposed within the large bore for pro-

2

teeting the packing means against the eroding effects of the high velocity fluid jetting into the tubular mandrel through the ports.

Various other objects will be apparent from the following description taken in connection with the accompanying drawings, in which:

Fig. 1 shows a formation tester having the novel tool of the present invention incorporated therein.

Fig. 2 is an enlarged longitudinal central section through the tool of the present invention, being taken generally along line 2—2 of Fig. 1.

Fig. 3 is a view similar to Fig. 2 but showing the valve ports of the tubular mandrel as having been projected so as to allow formation fluid to enter the tubular mandrel.

Fig. 4 is a horizontal sectional view taken along line 4—4 of Fig. 2.

Fig. 5 is a horizontal sectional view taken along line 5—5 of Fig. 2.

Referring to the accompanying drawings, wherein similar reference characters designate similar parts throughout, Fig. 1 discloses a formation tester of the type shown in the patent to M. O. Johnston 2,073,107, granted March 9, 1937, and entitled "Well Testing Method and Apparatus Therefor," the formation tester disclosed in Fig. 1 differing in the respects to be named hereinafter.

The formation tester disclosed in Fig. 1 is similar to the formation tester disclosed in the above-identified patent in that the formation tester in Fig. 1 includes at its upper end a trip valve generally entitled 9 adapted to be opened by a go-devil dropped down the drill string, and an equalizing valve generally entitled 11 disposed below the trip valve and adapted to allow well fluid to bypass a packer 13 when the tool is being lowered into the well and adapted to be closed thereafter to prevent such bypassing action, said formation tester also including a perforated anchor 15 below the packer and into which the formation fluid from the formation zone is adapted to flow. There is also a retaining valve 45 included in the formation tester disclosed in the above-identified patent, and the present invention also includes a retaining valve, but which retaining valve is specifically different from the valve disclosed in the above-identified patent.

Referring to Figs. 2 through 5, the novel tool of the present invention includes a tubular mandrel generally entitled 17 which slidably extends into a tubular housing comprising a sub 19, a pipe section 21, and a retaining nut 23 threadedly connected together as shown. Surrounding

tubular mandrel 17 is a strong compression spring 25 bearing against retaining nut 23 at its lower end and against a threaded collar 27 at its upper end. Collar 27 threadedly engages the lower end of a connecting sub 29 which is connected to the upper portion of the formation tester. The upper end of tubular mandrel 17 also threadedly engages connecting sub 29 as is clearly shown in Fig. 2. Suitable set screws 31 may be provided on collar 27 to hold the collar in any position of adjustment relative to connecting sub 29. By adjustment of collar 27, the force exerted by compression spring 25 can be regulated.

Tubular mandrel 17 is slidably but non-rotatably received within sub 19 by having keys 33 formed thereon which are received within keyways formed in sub 19 (compare Figs. 2 and 4). Keys 33 are adapted to engage the lower end 23a of retaining nut 23 when the tubular mandrel 17 is moved upwardly relative to sub 19 to limit upward movement of the tubular mandrel relative to the sub, and are adapted to engage the lower ends 19a of keyways 35 to limit downward movement of tubular mandrel 17 relative to sub 19.

Keys 33 and keyways 35 establish a rotary drive between the drill string through tubular mandrel 17 to the drill section 21 and the parts therebelow, particularly to the packer 13 to enable the packer to be manipulated by manipulation of the drill string in an effort to remove the same. Keys 33 and keyways 35 are always in engagement and, therefore, always permit a rotary drive between the above mentioned parts at all times.

Adjacent its lower end, tubular mandrel 17 is laterally ported at 37 to provide valve ports to admit formation fluid into the tubular mandrel when the ports are projected below tubular sub 19 from the position shown in Fig. 2 to the position shown in Fig. 3. Normally, however, strong compression spring 25 is effective to move tubular mandrel 17 upwardly to a point where keys 33 engage the lower end 23a of lower retaining nut 23 to dispose ports 37 within the confines of the tubular sub 19.

The lower end of tubular mandrel 17 is closed by a downwardly opening spring-loaded circulation valve 39.

In order to prevent the leakage of fluid between the exterior of tubular mandrel 17 and the interior of the lower end of sub 19, suitable upper packing 41 and lower packing 42 are provided on the lower end of tubular mandrel 17. Preferably, this packing takes the form of O rings received within annular grooves provided around tubular mandrel 17. When the lower end of tubular mandrel 17 is projected below the lower end of sub 19 into the large bore provided by pipe section 21, such as by a partial imposition of the weight of the drill string on tubular mandrel 17, packing 42 will be exposed. As previously mentioned, the interior of the drill string and formation tester will be normally at a relatively low pressure, approximately atmospheric pressure, whereas the formation fluid below the packer 13 will be at a relatively high pressure. The fluid, therefore, jets at high velocity into tubular mandrel 17 through ports 37, said fluid having a high eroding effect.

To protect packing 42 from this high velocity fluid, a sleeve-type cage 45 is provided and threadedly engages at its upper end the lower end of sub 19. Cage 45 is laterally ported at 47 and grooved at 49 (compare Figs. 2 and 5) to allow

formation fluid to flow upwardly through groove 49 into ports 47, through ports 37 and into the tubular mandrel and upwardly into the formation tester and drill string.

As shown in Fig. 5, the external diameter of cage 45 is less than the interior diameter of tubular drill section 21, and, therefore, cage 45 slidably fits into pipe section 21. The above construction of cage 45, therefore, leaves a sleeve or collar portion 51 disposed in depending relationship with respect to the lower end of sub 19 and adapted to surround packing 42 when tubular mandrel 17 is projected below sub 19 to a position where keys 33 engage shoulders 19a. Therefore, when the packing 42 is projected below sub 19, it is disposed within the confines of collar or sleeve portion 51 and therefore protected from the eroding effect of the high velocity formation fluid jetting into tubular mandrel 17. It follows, therefore, that when the packing is once again disposed within sub 19, the undamaged packing will be effective to prevent leakage of formation fluid out of mandrel 17 and also prevent well fluid from entering the mandrel and contaminating the trapped formation fluid therein.

The tool of the present invention is operated in the following manner. The tool may be used in the form shown in Fig. 2 and merely connected at its upper end to the lower end of a string of 30 drill pipe or it may be connected in a formation tester as shown in Fig. 1. When incorporated in a formation tester as shown in Fig. 1, the tester is lowered into the well bore and the packer 13 set. A part of the weight of the drill string is 35 then imposed on tubular mandrel 17 to compress spring 25 and project ports 37 below the lower end of sub 19 and in alignment with ports 47 of sleeve-type cage 45. The packing 42 will be disposed within the confines of collar or sleeve portion 51 of sleeve-type cage 45, and therefore, protected.

A go-devil is then dropped down the drill string to open trip valve 9 to permit formation fluid, which flows into anchor 15 upwardly through the lower portion of the formation tester, through ports 47, ports 37 and into tubular mandrel 17, to flow up into the upper portion of the formation tester and into the drill string.

After a sufficient time has elapsed to permit the entrapment of the desired amount of formation fluid sample, the weight of the drill string is relieved and the drill string removed.

It may be, however, that the packer 13 becomes tightly stuck in place and cannot be readily removed. In such a case, fluid may be pumped down through the drill string, through tubular mandrel 17 and out through spring-loaded valve 39, down through the lower portion of the formation tester, out through the perforated anchor 15 to the underside of packer 13 to urge the packer to unseat. By an upward pull on the drill string in combination with the upward fluid force against the underside of packer 13, the packer can be unseated.

The present invention, therefore, provides an oil well tool by which a formation fluid sample can be readily taken by partially imposing the weight of the drill string on the tool to compress the strong compression spring and project the ported portion of the mandrel below sub 19 to expose the ports thereof. Thereafter, the sample can be readily trapped by merely relieving the weight of the drill string.

The present invention also provides for a novel arrangement for protecting packing in the man-

drel from the high velocity fluid jetting into the tubular mandrel.

While I have shown the preferred form of my invention, it is to be understood that various changes may be made in its construction by those skilled in the art without departing from the spirit of the invention as defined in the appended claims.

Having thus described my invention, what I claim and desire to secure by Letters Patent is:

1. An oil well tool, comprising a tubular housing adapted to be fixed in a well bore and having an upper small bore and a lower large bore formed one above the other in said housing, a tubular mandrel slidably received within the small bore and being laterally ported adjacent its lower end and being normally disposed in a position with the ported portion disposed within the small bore, the lower end of the mandrel being closed by an upwardly urged downwardly opening check valve, whereby communication between the interior of the mandrel and the large bore may be established by supplying fluid under pressure to the interior of the mandrel, packing on the mandrel below the ports normally disposed within the small bore and sealingly engaging the walls thereof, spring means urging the mandrel upwardly relative to the housing, whereby the ported portion of the mandrel can be projected into the large bore by forcing the mandrel downwardly relative to the housing against the resistance of said spring means, means for protecting the packing, when exposed, from the eroding effects of high velocity fluid jetting into the mandrel through the ports thereof, said means comprising a laterally ported cage disposed within and spaced from the walls of the large bore, carried by the housing, and sealingly engaging the lower end of said mandrel, and means slidably but non-rotatably connecting the mandrel and housing to maintain vertical alignment between the mandrel ports and the cage ports so that when the mandrel is forced downwardly, the mandrel ports will be brought into registry with the cage ports.

2. An oil well tool, comprising a tubular housing adapted to be fixed in a well bore and having

an upper small bore and a lower large bore formed one above the other in said housing, a tubular mandrel slidably received within the small bore and being laterally ported adjacent its lower end and being normally disposed in a position with the ported portion disposed within the small bore, the lower end of the mandrel being closed by an upwardly urged downwardly opening check valve, whereby communication between the interior of the mandrel and the large bore may be established by supplying fluid under pressure to the interior of the mandrel, packing on the mandrel below the ports normally disposed within the small bore and sealingly engaging the walls thereof, spring means urging the mandrel upwardly relative to the housing, whereby the ported portion of the mandrel can be projected into the large bore by forcing the mandrel downwardly relative to the housing against the resistance of said spring means, means for protecting the packing, when exposed, from the eroding effects of high velocity fluid jetting into the mandrel through the ports thereof, said means comprising a laterally ported cage disposed within and spaced from the walls of the large bore, carried by the housing, and sealingly engaging the lower end of said mandrel, said cage having grooves formed in the exterior thereof of extending from the cage ports to the lower end of said cage to provide ready passage of fluid from the lower end of the cage to the cage ports, and means slidably but non-rotatably connecting the mandrel and housing to maintain alignment between the mandrel ports and the cage ports so that when the mandrel is forced downwardly the mandrel ports will be brought into registry with the cage ports.
